APRON AND EJECTOR CONTROL FOR
CARRY-TYPE SCRAPERS

Donald E. Murray, Modesto, Calif.

Application May 28, 1946, Serial No. 672,823

4 Claims. (Cl. 37—126)

1

This invention relates to earth digging and carrying equipment and is directed to a carry type scraper for digging, loading, transporting and dumping earth.

The object of the invention is to provide a type of scraper in which the several operating parts are preferably controlled through a very simplified type of hydraulic cylinder assembly and in which the cycle of loading, transporting and emptying the scraper may be carried out and controlled by the driver of the tractor or other prime mover connected to the scraper.

A further object of the invention is to produce a practical device and one which will be exceedingly effective for the purpose for which it is designed.

These objects are accomplished by means of such structure and relative arrangement of parts as will fully appear by a perusal of the following specification and claims.

In the drawings:

Figure 1 is a longitudinal sectional view through the scraper showing the parts as they appear when the scraper has been loaded and is ready for transport.

Figure 2 is a side elevation showing the front apron or gate of the scraper raised and in the position it assumes before the tail gate of the scraper has been raised to complete the dumping of the load from the scraper.

Figure 3 is a longitudinal sectional view showing the position of the parts at the time the load in the scraper has been completely dumped.

Figure 4 is a diagrammatic outline of the cable system which is operable to consecutively first raise the front apron and then lift the tail gate to accomplish the dumping of the load from the scraper.

Figure 5 is a fragmentary perspective view showing the relative positions of two of the operating sheaves of the device.

Referring now more particularly to the characters of reference on the drawings, the numeral 1 designates the rear main frame of the scraper on which are carried spaced side plates 2. The frame 1 is supported on rear wheels 3 and is turnable about the axis 4 thereof for the purpose of raising and lowering the side walls 2 with respect to the ground.

Toward but spaced somewhat from the forward end of the side walls 2 is a scraping or cutting blade 5 which projects between the side walls 2 and extends to a point a short distance below the lower edge of said side walls. Pivotally immediately back of the blade 5, as at 6, is a combination bottom and back plate unit 7 and

2

8, respectively, which with the side plates 2 form an earth receiving scraper bowl which receives the dirt scraped up by the blade 6 with the forward movement of the scraper. At the top of the portion 8 is a stop 9 which engages a co-operating stop 10 on a cross beam 11 of the frame 1 when the unit 7—8 is in its lowered position.

Secured to the forward ends of the side walls 2 is an upwardly projecting arch frame 12 and projecting forwardly from the front end of the side walls 2 are straps 13. 14 is a draft yoke having spaced apart and diverging arms 15 at its lower end and which arms 15 are pivotally connected to the straps 13 as at 16. The draft yoke 14 is supported by a front wheel truck 17 projecting forwardly from which is a draft bar 18 for connection with a tractor or other prime mover. Pivotally connected adjacent the upper portion of the yoke 14, as at 19, is a hydraulic cylinder and piston unit 20; the projecting piston rod 21 of which is pivotally connected, as at 22, to a bracket 23 projecting forwardly from the upper side of the arch frame 12. Fixed rigidly to and projecting from the top of the arch frame 12 is a hydraulic cylinder and piston unit 24 which at its other end is connected to a supporting bracket 25 upstanding from the cross beam 11. On the outer end of the piston rod 26 of this unit is a sheave housing 27 in which is journaled a sheave 28. Projecting from the top of the arch frame 12 is a sheave housing 29 in which is journaled a sheave 30. Spaced from the housing 29 is a similar housing 31 projecting from the arch frame 12 and in which is journaled a sheave 32. On a cross beam 33 secured to the arch frame 12 at a point below the top of the arch is still another sheave housing 34 in which is journaled a sheave 35. Apron arms 36 are pivoted to the side plates 2, as at 37, and project forwardly beyond the free arms of said side plates 2 and support a front apron 38 which extends, when in lowered position, between the side plates 2 and against the blade 5 in order to form a front closure for the scraper bowl. A cable 39 is fixed adjacent the top edge of the apron 38 and extends upwardly over the sheave 30 then around the sheave 28 and over the sheave 32 and then under the sheave 35 and hence to a point of connection with the upper edge of the plate 8.

Guide rod 40 is fixed at one end to the housing 31 and a guide sleeve 41 is fixed to the housing 27 and the rod 40 telescopes into the sleeve 41. A rod 42 is pivoted to the top edge of the apron 38, as at 43, and is slidably mounted through a sleeve 44 pivoted on a bracket 45 se-

cured to the cross beam 33. A sheave 46 is journaled in the bracket 45 and a sheave 47 is journaled in a sheave housing 48 secured on the cross beam 11. A cable 49 is fixed to the upper end of the rod 42, as at 50, and extends downwardly around the sheave 46 and then around the sheave 48 and is hence fixed to the upper end of the sleeve 41. A suitable source of hydraulic pressure will in practice be provided on the tractor or other convenient place and controlled conduits will lead therefrom to the two hydraulic cylinders 20 and 24. These are conventional, however, and it is not deemed necessary to show the same herein for the operation of the scraper.

In Fig. 2 the scraper is shown with the front apron 38 raised to clear the front end of the scraper bowl. When in this position and the digging operation is to be carried out, the pressure is introduced into the cylinder 20 to move the piston rod 21 downwardly. This action causes the connection between the members 13 and 15 to hinge about a point 16 to lower the scraper bowl 2-7-8 to a position to bring the cutting blade 5 into the ground into cutting position, the scraper bowl then moving about the axis 4 of the wheels 3 as a turning axis. The scraper is then drawn forward, the blade 5 cuts into the earth and scrapes and loosens the same, and as it is scraped, the dirt moves back into and fills the scraper bowl 2-7-8. Pressure is then admitted to the cylinder 24 to move the piston rod upwardly. This slackens the cable 39 and allows the apron 38 to drop downwardly toward a closed position. The rod 42, at this time slides downwardly through the sleeve 44 as the piston rod 26 thus moves upwardly; the sleeve 41 also moves upwardly sliding over the guide rod 40. This action causes the said sleeve 41 to take up any slack occurring in the cable 49 occasioned by the downward movement of the rod 42. Just as the apron 38 approaches closed position over the scraper bowl the slack in the cable 49 is all taken out so that the last short movement of the sleeve 41 pulls the cable 49 taut and exerts a pulling action downwardly on the rod 42 at the point 50 thus forcedly and positively closing the apron 38 against the blade 5 and holding it in such closed position.

Reversed pressure is then applied to the cylinder 20 causing the piston rod 21 to move outwardly and exerting pressure upwardly against the arch frame 12 and lifting the entire scraper bowl and apron with the load of dirt therein upwardly and into transport position.

The loaded scraper is then conveyed to the point where the load is to be emptied. When this point is reached pressure is admitted to the cylinder 24 to drive the piston rod 26 outwardly and downwardly. This action tends to extend the cable 39 which action at first takes up the slack in the cable and then raises the apron 38 to its limit of upward movement as shown in Fig. 2. Continued movement of the piston rod 26 further extends the cable which thereafter exerts a pull on the top of the plate 8 and tilts the unit 7-8 on its pivot 6 to dump the load as shown in Fig. 3. As the apron 38 rises and the rod 42 pushes upward it pulls on the cable 49 but said cable is being progressively slackened as the piston rod 26 moves outwardly and the sleeve 41 moves over the guide 40 so as to permit of the upward movement of the rod 42 and said cable 49, the slackened cable 49 being shown in Fig. 3.

From the foregoing description it will be readily seen that there has been produced such a de-

vice as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful and upon which Letters Patent is desired:

1. A scraper comprising a scraper bowl which includes a rear frame and a front frame and side plates connecting the frames, a load ejecting member movable forwardly between the side plates, a load retaining apron positioned in front of the side plates and pivoted for swinging movement in a vertical plane, a hydraulic cylinder and piston unit rigidly connected to said frames and extending longitudinally of the scraper bowl, such unit including a piston rod projecting beyond one end of the cylinder, a sheave journaled in the outer end of the piston rod, a pair of sheaves mounted on the front frame in spaced relation to each other, a third sheave journaled on said front frame in a plane below said pair of sheaves, a cable fixed to the apron and extending over one of said pair of sheaves thence around the sheave on the piston rod, hence over the other of said pair of sheaves thence under said third sheave, and means connecting the cable with the ejecting member.

2. A combination as in claim 1 and including therewith a means for effecting a positive pressure against the apron as it approaches its lowermost position.

3. A combination as in claim 1 and including therewith a means for effecting a positive pressure against the apron as it approaches its lowermost position, such latter means including an upstanding rod pivoted on the apron, a sleeve journaled on the front frame, the rod being slidable through the sleeve, and means for applying pressure to said rod.

4. A scraper comprising a scraper bowl which includes a front frame and a rear frame, a load retaining apron positioned in front of the bowl and pivoted for swinging movement in a vertical plane, cable means to so swing said apron, an upstanding rod pivoted to the apron, a sleeve journaled on the front frame, the rod being slidable through the sleeve, a hydraulic cylinder and piston unit mounted on the frames and including a projecting piston rod, a guide pin fixed to the front frame, a guide sleeve fixed to the piston rod and being slidable over the pin, a sheave journaled in the front frame and a sheave journaled on the rear frame, and a cable fixed to the sleeve, such cable extending first around the sheave on the rear frame, thence under the sheave on the front frame, and means connecting said cable to the rod at a point above said last named sheave.

65 DONALD E. MURRAY.
